ATTORNEY.

UNITED STATES PATENT OFFICE

OLIVER C. PATTERSON, OF COMPTON, CALIFORNIA

WIRE-CABLE CLAMP

Application filed January 14, 1929. Serial No. 332,466.

This invention relates to a wire cable clamp by means of which a cable or a plurality of cables may be securely gripped for the purpose of holding the cable against movement, for example, as a guy wire, or other similar or analogous uses.

An object of my invention is to provide a clamp particularly useful around an oil well derrick and which may be adapted for various uses such as drawing the cable over the crown block, holding the sand line against displacement, connecting various lengths of cable, and the like.

A further object is to provide a wire cable clamp which is simple in construction and effective in use.

Other objects, advantages, and features of invention may appear from the accompanying drawing, the subjoined detailed description, and the appended claims.

In the drawing:

Figure 1 is a side elevation of my clamp with parts broken away to show interior construction.

Figure 2 is a plan view of the clamp.

Figure 3 is a side elevation of my clamp in open position.

Figure 4 is a plan view of a slightly modified form of clamp, one side being open.

Figure 5 is a side elevation of the same.

Figure 6 is a side elevation of still another modified type of clamp.

Figure 7 is a view taken at right angles to that shown in Figure 6.

Referring more particularly to the drawing, my clamp 1 consists of two sections 2, 3 which are hingedly connected at the rear, as shown at 4. The front meeting edges of the sections 2, 3 are staggered so that greater strength is provided against a longitudinal pull through the clamp. Bosses 5, 6 are provided on the sections 2, 3, respectively, and a bolt 7 extends therethrough, whereby the two sections are securely held together and are clamped around the cable. Obviously, a plurality of bosses 5, 6 may be provided throughout the length of the clamp if it is found necessary.

The sections 2, 3 are each provided with a half-bore 8, 9, respectively, said half-bores

being so arranged that when the clamp is closed a circular bore is provided to receive the cable 10. These bores are preferably corrugated or ribbed so that the cable is more securely clamped.

The lower ends of the sections 2, 3 are threaded, as shown at 11, and a socket 12 screws thereon which socket may be provided with a hook or an eye, as shown at 13. This socket further holds the two sections of the clamp securely together and prevents any movement thereof. A shoulder 14 is provided on the sections 2, 3 against which the socket 11 screws. A tapered opening 15 is provided at the lower end of the clamp 1 to receive the enlarged end of the cable when my clamp is used as a rope socket.

If desired, a flange 16 may be provided on top of the section 3 whereby my clamp can be fastened to the derrick head board, or the like. A slip 17 is slidably mounted in the section 2 and is actuated by the lever 18, which lever is connected to the slip by the link 19. A pair of ears 20 are formed on the top of the section 2 between which the lever 18 is pivoted. With this latter arrangement my clamp is particularly useful for holding the sand line or the like, against movement while said line is not in use.

In Figures 4 and 5 I have illustrated a clamp which can conveniently hold two strands of cable and this arrangement comprises a pair of clamps 21, 22, each of which comprises a stationary segment 23 and a moving segment 24 pivotally mounted to the section 23, as at 25. Each of the sections 24 are held clamped around a cable by a bolt 26. An eye 27 is provided on the stationary section 23 by means of which the clamp can be suspended.

In Figures 6 and 7 I have shown an arrangement similar to that shown in Figures 1 and 2 which comprises a pair of hingedly connected sections 28, 29 fastened together by the bolt 30. A loop 31 is integrally formed with the section 28, the purpose being to fasten a chain or the like, thereto for the purpose of drawing a cable over the crown block, or another clamp may be suspended below the first clamp, or any other

suitable arrangement may be entered into which is found necessary or convenient.

Having described my invention, I claim:

1. A wire cable clamp comprising a pair of sections hingedly secured together at one side thereof, a bolt securing said sections together at the other side thereof, said sections having a bore therethrough to receive the cable, and the meeting edges of said sections being staggered to provide greater strength, and a socket screwed onto the bottom of said sections.

2. A wire cable clamp comprising a pair of sections hingedly secured together at one side thereof, a bolt extending through and securing said sections together at the other side thereof, said sections having a bore therethrough to receive the cable, and the meeting edges of said sections being staggered to provide greater strength, a slip in one of said sections, mounting means for said slip whereby it is movable longitudinally in said bore, and manual means connected to said slip whereby the slip may be moved longitudinally of the bore, said slip extending partly to the bore to grip the cable.

3. A wire cable clamp comprising a pair of sections hingedly secured together at one side thereon, a bolt securing said sections together at the other side thereof, said sections having a bore therethrough to receive the cable, and the meeting edges of said sections being staggered to provide greater strength, a slip in one of said sections, mounting means for said slip whereby it is movable longitudinally in said bore, and manual means connected to said slip whereby the same may be moved longitudinally of the bore, said last named means comprising a lever pivotally mounted on the clamp, and a link connecting said slip and said lever, said slip extending partly to the bore to grip the cable.

4. A wire cable clamp comprising a pair of sections hingedly secured together at one side thereof, a boss formed on each of said sections on the one side thereof, a bolt extending through said bosses, a mounting flange integrally formed on one of said sections, said sections having a central bore extending therethrough, a slip, means mounting the slip for longitudinal movement in one of said sections, said slip extending partly into said bore, a lever pivotally mounted on one of said sections, and a link connecting said lever and said slip, whereby the slip is moved longitudinally, said slip extending partly into the bore to grip the cable.

5. A wire cable clamp comprising a pair of sections hingedly secured together at one side thereof, a boss formed on each of said sections on the one side thereof, a bolt extending through said bosses, a mounted flange rising above and integrally formed with one of said sections, each of said sections having

a half bore extending therethrough, a slip in one of said sections, means mounting the slip for longitudinal movement in said sections, said slip extending partly into said bore whereby the cable or the like is gripped, a pair of ears rising from the section in which the slip is mounted, a lever pivotally mounted between said ears and a link pivotally secured to said lever and to the slip whereby the slip is moved longitudinally.

In testimony whereof, I affix my signature.

OLIVER C. PATTERSON.
